(57) **CLAIM**

The ornamental design for a storage container, as shown.

DESCRIPTION

FIG. 1 is a top perspective view of a storage container in accordance with the present invention;

FIG. 2 is a left view thereof;

FIG. 3 is a right view thereof;

FIG. 4 is a front view thereof;

FIG. 5 is a back view thereof;

FIG. 6 is a top view thereof;

FIG. 7 is a bottom view thereof;

FIG. 8 is a bottom perspective view thereof;

FIG. 9 is a top perspective view of a base of the storage container;

FIG. 10 is a left view thereof;

FIG. 11 is a right view thereof;

FIG. 12 is a front view thereof;

FIG. 13 is a back view thereof;

FIG. 14 is a top view thereof;

FIG. 15 is a bottom view thereof;

FIG. 16 is a bottom perspective view thereof;

FIG. 17 is another top perspective view thereof;

FIG. 18 is another bottom perspective view thereof;

FIG. 19 is a top perspective view of a lid of the storage container;

FIG. 20 is a left view thereof;

FIG. 21 is a right view thereof;

FIG. 22 is a front view thereof;

FIG. 23 is a back view thereof;

FIG. 24 is a top view thereof;

FIG. 25 is a bottom view thereof;

FIG. 26 is a bottom perspective view thereof;

FIG. 27 is another top perspective view thereof;

FIG. 28 is another bottom perspective view thereof; and,

FIG. 29 is a top perspective view of the lid and base separated.

The lid and base are shown separately for convenience of illustration only.
